UNITED STATES PATENT OFFICE.

JOHN C. W. ADOLPH HILDEBRANDT, OF NEW YORK, N. Y.

COLLAPSIBLE-TUBE HOLDER.

Application filed July 28, 1923. Serial No. 654,316.

To all whom it may concern:

Be it known that I, JOHN C. W. ADOLPH HILDEBRANDT, a citizen of the United States, residing in the city, county, and State of New York, have invented new and useful Improvements in Collapsible-Tube Holders, of which the following is a specification.

This invention relates to a tooth paste tube holder and tooth paste dispenser.

10 It is an object of the invention to provide a stationary holder for the collapsible tubes, in which tooth paste, shaving cream and the like are purchased, which can also be used to extrude or force the paste out of the

15 mouth of the tube as desired.

Prior devices for this purpose have been provided with relatively movable parts by which the ends of the tubes were folded over to force the paste from the mouth of the 20 tube. The construction of a paste dispenser with such relatively movable parts of sufficient durability to withstand the use to which it is put involves considerable expense.

25 It is an object of this invention to reduce the cost of paste dispensers of this type by providing a dispenser with fixed parts which will be more economical to manufacture, will have all the utility of the prior devices 30 and will be less likely to become broken or get out of order.

In the drawings, which illustrate preferred embodiments of the invention,

Fig. 1 is a perspective view of the holder 35 with a tube of paste mounted therein.

Fig. 2 is a plan view of a modified form of the invention.

Fig. 3 is an end view of the holder and tube illustrating how the paste is forced 40 from the tube.

In the embodiment illustrated in Fig. 1, the holder comprises an arm 1, provided with a screw threaded extension 2 for insertion into the walls of the bath room to hold 45 the holder. A shield 3 is provided between the arm 1 and the screw threaded portion to make a neater appearance and conceal

the hole into which the screw 2 is inserted. The shield 3 could of course be omitted without detracting from the usefulness of 50 the holder. The arm 1 is slotted at 4 to receive the flattened end 5 of the paste tube 6.

In the modification illustrated in Fig. 2, the arm 1, shield 3, and slit 4 are substantially duplicates of the corresponding parts of the modification illustrated in Fig. 1 with the exception that the shield 3 is provided with a number of perforations around its outer edge through which screws 7 may project into the walls of the room.

The operation of the device for extruding the paste is illustrated in Fig. 3, it being merely necessary to remove the cap 14 from the tube and wind or wrap the tube about the arm 1 to squeeze the walls of the tube together and force the paste out where it may be taken up on the tooth brush, shaving brush, or the like.

Various modifications may be made within the scope of the appended claims without departing from the spirit and scope of the invention, it being my intention to claim the same as broadly as the state of the prior art will permit.

What I claim is:

1. In a collapsible tube holder, a unitary structure of circular cross section and comprising in itself a projecting member longitudinally slotted to receive the tube body, 80 and a combined shield and supporting member adapted to engage a support and to conceal defacement caused by said engagement.

2. In a collapsible paste tube holder, a unitary structure of circular cross section 85 provided with a projecting portion having a longitudinal tube engaging slot, a supporting portion having threaded wall-engaging means, and a shield portion intermediate the aforesaid portions and concealing wall defacement caused by said supporting portion.

In testimony whereof I have affixed my signature to this specification.

JOHN C. W. ADOLPH HILDEBRANDT.
